UNITED STATES PATENT OFFICE

165,137

APPARATUS FOR DETERMINING THE APPLICATION OF COSMETICS

Serge de Gorin, Hollywood, Calif., assignor to Coty, Inc., Wilmington, Del., a corporation of Delaware

Application August 4, 1951, Serial No. 16,158

Term of patent 14 years

(Cl. D57—1)

To all whom it may concern:

Be it known that I, Serge de Gorin, citizen of the United States, residing at Hollywood, in the county of Los Angeles and State of California, have invented a new, original, and ornamental Design for an Apparatus for Determining the Application of Cosmetics, of which the following is a specification, reference being had to the accompanying drawing, forming part thereof.

In the drawing:

Fig. 1 is a front elevational view of an apparatus for determining the application of cosmetics, showing my new design;

Fig. 2 is a right side elevational view;

I claim:

The ornamental design for an apparatus for determining the application of cosmetics, as shown.

SERGE DE GORIN.
